UNITED STATES PATENT OFFICE.

MARTIN BOURKE, OF YOUNGSTOWN, OHIO.

BOAT-DETACHING APPARATUS.

SPECIFICATION forming part of Letters Patent No. 251,690, dated January 3, 1882.

Application filed July 15, 1881. (No model.)

To all whom it may concern:

Be it known that I, MARTIN BOURKE, a citizen of the United States, residing at Youngstown, in the county of Mahoning and State of Ohio, have invented certain new and useful Improvements in Raising and Lowering Boats; and I do hereby declare that the following is a full, clear, and exact description of the same, reference being had to the annexed drawings, making a part of this specification, and to the letters and figures of reference marked thereon.

Figure 1 of the drawings is a perspective view of one end of a boat, showing the application of my invention. Fig. 2 is a detail view, in perspective, of my invention disconnected from the boat; and Fig. 3 is a modification thereof.

The present invention has relation to that class of devices for detaching or releasing life 20 or other boats from their connections after being launched from off the ship, which is fully set forth in my patent of December 17, 1878, No. 210,908; and the invention is designed as an improvement thereon, the object being to 25 provide a device that can be attached to the inside of the boat as well as the outside and readily and effectually operated in freeing the boat from its connections immediately upon 30 coming in contact with the surface of the water. These objects I attain by the construction substantially as shown in the drawings, and hereinafter described.

In the accompanying drawings, A represents a sectional view of one end of a boat of the 35 usual construction.

Within the boat A, at each end thereof, is suitably connected, by bolts or other means, a standard, B, of metal, having holding devices a. I have shown in Fig. 2 these devices as being in the form of arms projecting from each side of the standard; but I do not desire, however, to be understood as confining myself to such construction, as it may be variously modified, so long as a shoulder or bearing-surface is presented for the shoulders b upon the clutch C.

It will be seen by reference to Fig. 3 that the holding devices are somewhat different from those shown in Fig. 2. In place of the holding 50 devices being in the form of arms projecting

from each side of the standard they are in the form of an inclined notch, and the clutch having an inclined shoulder to correspond, so that it will seat itself in the notch and hold itself in connection with the standard until the boat 55 is sufficiently lowered to be brought in contact with the water, when it will release itself automatically. It will be understood that the same result is obtained by the construction as shown in Fig. 3, but by a slight modification, 60 such change, as coming within the spirit of my invention, I reserve the right to make.

The clutches at each end of the boat are connected in any suitable manner to ropes c, passing over suitable pulleys connected to swinging 65 arms suspended from the sides of the ship, this construction, and also the manner of raising and lowering the boat, being fully explained in my former patent, and therefore further description is deemed unnecessary.

The clutches C are securely held in contact with the standards B by bolts d, which enter holes in the standards and clutches. These bolts, which are covered by my former patent, are operated in the same manner, said bolts 70 being connected to a lever, e, pivoted to a suitable frame connected to the interior of the boat. When the ends of the bolts d are engaged with the holes in the standards and clutches, the two, as previously stated, are securely locked 75 together; but in lowering the boat the bolts may be drawn at any time without danger of the clutches disconnecting themselves from the standards, owing to the weight of the boat, but after the bolts are drawn, the boat, immediately upon coming in contact with the water, 80 will automatically disconnect itself from its fastenings.

The clutches C, I prefer to form with a hooked end, f, so that when it is desired to raise the 90 boat said hooks are made to engage with rings g, secured to the interior of the boat, this being considered the most effective and simple manner of attaching the boat to the ropes c, as it would be inconvenient to engage the 95 clutches with the standards and lock the bolts, especially where only one person is in the boat.

Having now fully described my invention, what I claim as new, and desire to secure by Letters Patent, is—

The standards B, secured to each end of the boat A and extending up inside thereof and provided with suitable holding devices, *a*, in combination with the clutches C, having shoulders *b*, for engaging with the holding devices on the standards, and the sliding bolts *d*, passing through the standards and entering the clutches, substantially as and for the purpose set forth.

In testimony that I claim the above I have to hereunto subscribed my name in the presence of two witnesses.

MARTIN BOURKE.
